J. J. McGUCKIN

ROTATABLE CUTTING TOOL

Filed Dec. 2, 1924

INVENTOR,
John J. McGuckin.
BY Andrew Wilson,
ATTORNEY,

UNITED STATES PATENT OFFICE.

JOHN J. MCGUCKIN, OF BROOKLYN, NEW YORK, ASSIGNOR TO LOUIS SCHWAB, OF NEW YORK, N. Y., DOING BUSINESS UNDER THE NAME OF STEVENS & COMPANY.

ROTATABLE CUTTING TOOL.

Application filed December 2, 1924. Serial No. 753,427.

My invention relates to rotatable cutting tools, and particularly to tools of a class which may be used for resurfacing, reaming and drilling, it being my object to produce such a tool which is both simple in construction, positive in application and efficient and durable in operation.

In the drawings, Fig. 1 is an elevation of my improved tool showing it applied to an axle fork; Fig. 2 is a view of the tool taken on the line 2—2 of Fig. 1; Fig. 3 is an end view of a cutting end of the tool; Fig. 4 is an elevation of a modified form of cutter sleeve; Fig. 5 is an end view of the same, looking down on Fig. 4; Fig. 6 is an end view of the upper member of the cutter sleeve shown in Fig. 4, looking up from the line 6—6; Figs. 7 and 8 are elevations of modifications; and Fig. 9 shows a modified form of spindle.

In all the figures similar parts are designated by similar reference numerals.

The tool is assembled upon a bolt or spindle 1, adapted to pass through the standard openings in an axle fork. Upon this bolt are slid two sleeves 3, 4, provided upon their outer ends with transverse cutting elements 5, 5, which are preferably formed of straight parallel ribs, of substantially equal pitch on each side, so that they will cut equally when rotated in either direction. The inner ends of these sleeves 3, 4, are provided with projecting flanges as 5, 5, and 6, 6, respectively, which are adapted to be straddled by the forked end 7 of an operating handle 8, the parts being preferably so proportioned that when the fork 7 is slid between the sleeves 3 and 4 as shown in Fig. 1, the cutting faces of the sleeves will normally lie approximately close to the inner faces of the fork. The jaws of the fork 7 bearing against the shoulders of the sleeves 3, 4, are preferably elliptical, as indicated in the drawings, the proportions of the ellipses being determined by the amount of displacement desired for the sleeves 3 and 4.

In an axle fork as shown in Fig. 1, the cutters may be turned to and fro by swinging the handle 8; while the cutters may be held to duty by pressing down or raising the handle 8 so as to cause the elliptical jaws to act as cams forcing the cutting sleeves 3 and 4 strongly to duty against the

inner faces of the fork; and at the same time the cutters can be instantly released by withdrawing the fork or by swinging the handle 8 into horizontal position so as to release the cam action of the fork.

By giving the cutting ribs of the sleeves 3 and 4 equal pitches in both directions, their cutting action against the fork surfaces will be equal in both directions of their rotation, under equal stresses on the operating handle.

It frequently happens that the inner face of the upper arm of the fork requires much more work by a resurfacing tool than the face of the lower arm of the fork, for the weight of the car is carried by the upper arm of the fork. If, therefore, it is desired not to cut away the face of the lower arm of the fork, a sleeve 4, having a plain surface, instead of the ribbed cutters 5, may be substituted for the sleeve 4. In that case the cutter 3 will resurface the upper arm of the fork, while the lower arm will not be cut in the operation of the tool.

In Figs. 4, 5 and 6 I have shown a modified form of cutter sleeve wherein it is formed in two sections, the upper of which 9 is provided with pitched cutting teeth 10, 10, adapted to cut in one direction, and the two sections are provided with intermeshing, radial teeth 11, 11, of equal lateral pitch, so that, when the pressure of the lever 8 is released, the lower section 12 may be turned back relative to the upper section, but will grip it, when pressure is applied, to drive it forward. If this modification is used, the sleeve 4 will be given a suitable length to compensate for any difference in the combined length of the upper sections 9, 12.

Fig. 7 shows another modification wherein the upper cutter sleeve 13 and the lower terminal 14, are secured upon a spindle 15, the sleeve 13 being fixed, as by a cotter bolt 16, while the terminal 14 has a sliding connection with the spindle, which is permitted by the recess 17 in the spindle receiving the end of a set screw 18.

The lower end of the terminal 14 is preferably pointed to facilitate its gripping a plain surface if it is presented in the use of the tool. In this form of the tool the spindle and sleeves form a unitary assembly

which is a convenient arrangement for a mechanic.

Another modification is shown in Fig. 8, wherein the spindle is given the form of a drill 19, over which a short cutting sleeve 20 may be slid, if the tool is to be used for resurfacing, the flange 21 on sleeve 20, interlocking with recess 22 in sleeve 23 which is attached to the spindle drill by cotter bolt 24. The same movement of the lever 8 which will press the surfacing sleeve to duty, will do the same for the drill.

If the spindle 25, shown in Fig. 9, is substituted for the drill 19 of Fig. 8, in combination with the terminal 14 of Fig. 7, the tool may be used for reaming purposes. It is obvious that the size of the element 19 may be varied to suit the special conditions to which the tool is to be applied.

20 It will be understood that details of construction of my invention may be modified as by the use of mechanical equivalents without departing from the scope of the claims. For the particular embodiment of 25 my invention which I have shown is to be considered as a typical and not as an exclusive form.

Having thus described my invention, what 30 I claim and desire to secure by Letters Patent of the United States is:—

1. In a rotatable cutting tool, the combination with a spindle of separable elements mounted thereon, and unitary means for rotating such separable elements and for producing relative displacement of them axially on the spindle to force them to duty in opposite directions.

2. In a rotatable cutting tool, the combination with a spindle of separable elements mounted thereon, and unitary means provided with gripping elements for rotating such separable elements and with cam elements for producing relative displacement of them axially on the spindle to force them to duty in opposite directions.

3. In a rotatable cutting tool, the combination with a spindle of separable elements mounted thereon, and unitary means consisting of a forked lever inserted between the separable elements for rotating them and for producing relative displacement of them axially on the spindle to force the tool to cutting duty.

4. In a rotatable cutting tool, the combination, with a guide spindle, of sleeve elements mounted thereon, one thereof being provided with a serrated end to form a cutter and unitary means for rotating the

cutter and for pressing it to duty by forcing it away from the other sleeve.

5. In a rotatable cutting tool, the combination, with a guide spindle, of sleeve elements mounted thereon, one thereof being provided with straight parallel serrations in one end to form a cutter and unitary means for rotating the cutter and for pressing it to duty by forcing the sleeves in opposite directions.

6. In a rotatable cutting tool, the combination, with a guide spindle, of opposed sleeve elements mounted thereon, each thereof being provided with a serrated cutter and unitary means for rotating the cutters and for pressing them to duty in opposite directions.

7. In a rotatable cutting tool, the combination, with a guide spindle, of sleeve elements mounted thereon, one thereof being provided with a serrated end to form a cutter and with engageable means at its opposite end and unitary means adapted to engage with said engaging means, to rotate the cutter, and to bear against the opposed ends of the sleeves to press the cutter to duty.

8. In a rotatable cutting tool, the combination, with a guide spindle, of sleeve elements mounted thereon, one thereof being provided with a serrated end to form a cutter and with engageable means at its opposed end and unitary means adapted to engage with said engaging means, to rotate the cutter, and being provided with cam elements to bear against the opposed ends of the sleeves to press the cutter to duty.

9. In a rotatable cutting tool, the combination, with a guide spindle of sleeve elements mounted thereon, one thereof being provided with cutting elements on its outer end and with a handle-fork engaging element, a handle, provided with a fork adapted to be inserted between said sleeves to straddle the spindle and to engage with the cutter to rotate the same, said fork being provided with a cam element for forcing the sleeves apart by swinging the handle in the plane of the spindle.

10. In a rotatable cutting tool, the combination, with a guide spindle, of sleeve elements mounted thereon, one thereof being provided with a terminal cutter and with engageable means at its opposite end, and unitary means adapted to engage with said engaging means, to rotate the cutter and to bear against the opposed ends of the sleeves to press the cutter to duty.

JOHN J. McGUCKIN.
